UNITED STATES PATENT OFFICE.

SWAN F. SWANSON, OF PUEBLO, COLORADO.

DUMPING-CAR.

No. 839,335.

Specification of Letters Patent.

Patented Dec. 25, 1906.

Application filed April 26, 1906. Serial No. 313,900.

To all whom it may concern:

Be it known that I, SWAN F. SWANSON, a citizen of the United States, residing at Pueblo, in the county of Pueblo and State of Colorado, have invented certain new and useful Improvements in Dumping-Cars; and I do declare the following to be a full, clear, and exact description of the invention, such as will enable others skilled in the art to 10 which it appertains to make and use the same.

My invention relates to improvements in dumping-cars, wagons, and the like; and it 15 consists in the construction, combination, and arrangement of parts hereinafter described and claimed.

The object of the invention is to improve and simplify the construction and operation of devices of this character, and thereby render the same more durable and efficient and less expensive.

The above and other objects are accomplished by the construction illustrated in the accompanying drawings, in which—

Figure 1 is a bottom plan view of the body of a dumping-car constructed in accordance with my invention. Fig. 2 is a vertical longitudinal sectional view taken on the plane indicated by the line 2 2 in Fig. 1. Fig. 3 is a 20 vertical transverse sectional view through the same, taken on the plane indicated by the line 3 3 in Fig. 1; and Fig. 4 is a detail sectional view taken on the plane indicated by the line 4 4 in Fig. 1.

The present embodiment of my invention is in the form of a rectangular car or wagon body 1, constructed of metal and having straight or vertical sides 2 and ends 3; but it will be understood that the improvements 40 may be applied to a car, wagon, or the like of any form and construction which may have either straight or inclined ends and sides and any number of swinging bottom-sections. Four bottom-sections 4 are shown in the drawings, and these are arranged in pairs and hinged at 5 to the inner faces of the sides 2 a short distance above the lower edges of the latter, so that they will swing downwardly and outwardly from the center of the car. 50 The lower portions of the sides and ends 2 3 of the body are strengthened by angle-metal bars 6 and flat bars or plates 7, and upon the inner or free longitudinal edge of two of the bottom-sections 4 are provided projecting ledges or tongues 8 to effect a tight joint between the meeting ends of the opposing bot-

tom-sections, as shown in Fig. 3. Between the side edges of the adjacent bottom-sections and at the ends of the body are transverse sills 9 in the form of I-beams, which 60 have secured upon their tops plates 10, the projecting edges of the latter being adapted to limit the upward swinging movement of the bottom-sections 4.

The bottom-sections 4 are swung open and 65 closed by rotating a lever, crank-handle, or the like 11 upon one end of a longitudinal shaft 12, journaled in suitable bearings upon the outer face of one of the sides 2 of the car-body. A pawl-and-ratchet locking device 13 70 is provided at said end of the shaft to hold the latter against rotation, and hence the bottom-sections 4 in their closed position. Upon the shaft 12 are secured pinions 14, which project through slots in the side 2 and mesh with 75 gears 15, secured on short shafts 16, extending through the I-beams 9 and the upwardly-extending arms or ends of U-shaped bearing-brackets 17, secured upon the bottom flanges of said I-beams, as shown in Fig. 4. Upon 80 said short shafts 16 on opposite sides of the I-beams are secured grooved pulleys or drums 18, to which are attached and upon which are wound chains or other flexible connections 19. The opposite ends of these chains 19 are 85 divided to provide two branches 20 21, which pass over guide-pulleys 23 upon the I-beams and have their ends attached to the eyes of bolts 23. The latter are mounted in the bent lower ends 24 of arms or brackets 25, secured 90 upon the bottom faces of the bottom-sections 4, as clearly shown in the drawings. It will be seen that when the shaft 16 is rotated in one direction the chains will be unwound from the drums 18 and the bottom-sections of 95 the car or wagon will swing to their lowered or opened position and that when it is rotated in the reverse direction said chains will be wound upon the drums 18 and the bottom-sections will be swung up to their elevated or 100 closed position. The pawl-and-ratchet device retains them in the latter position. Any suitable means may be provided for adjusting the length of the branches of the chains.

From the foregoing description, taken in 105 connection with the accompanying drawings, the construction and operation of the invention will be readily understood without requiring a more extended explanation.

Various changes in the form, proportion, 110 and the minor details of construction may be resorted to without departing from the prin-

2
ciple or sacrificing any of the advantages of this invention, as defined by the appended claims.

Having thus described my invention, what I claim as new, and desire to secure by Letters Patent, is—

1. A dumping-car or the like comprising walls, bottom-sections hinged to swing from said walls, beams connecting said walls, a long shaft upon one of said walls, short shafts upon said beams, gearing between said long and short shafts, guides upon said beams, depending bracket-arms upon said bottom-sections, winding-drums upon said short shafts, and flexible connections between said arms and said winding-drums, substantially as described.
2. A dumping-car or the like comprising walls, bottom-sections hinged to swing, from

said walls, beams connecting said walls, a long shaft upon one of said walls, short shafts upon said beams, gearing between said long and short shafts, guides upon said beams, depending bracket-arms upon said bottom-sections, winding-drums upon said short shafts, flexible connections between said arms and said winding-drums, a lever upon said long shaft, and a pawl-and-ratchet locking device between said long shaft and one of the walls of the car, substantially as described.

In testimony whereof I have hereunto set my hand in presence of two subscribing witnesses.

SWAN F. SWANSON.
